By Attorney

UNITED STATES PATENT OFFICE.

HENRY A. WEIHMAN, OF PHILADELPHIA, PENNSYLVANIA, ASSIGNOR TO
SIMONS, BRO. & CO., A CORPORATION OF PENNSYLVANIA.

DESIGN FOR A THIMBLE.

No. 38,659.

Specification for Design.

Patented July 9, 1907.

Application filed June 6, 1907. Serial No. 377,666. Term of patent 7 years.

To all whom it may concern:

Be it known that I, HENRY A. WEIHMAN, of the city and county of Philadelphia, State of Pennsylvania, have invented a new, original, and ornamental Design for Thimbles, of which the following is a specification, reference being had to the accompanying drawings, forming part thereof.

In the drawings, Figures 1 and 2 represent

views from opposite sides of the thimble, showing my new design.

I claim—

The ornamental design for a thimble, as shown.

HENRY A. WEIHMAN.
